ATTORNEY

UNITED STATES PATENT OFFICE.

CHARLES H. DOLAN, OF DORCHESTER, MASSACHUSETTS.

CARD GAME.

Application filed June 27, 1927. Serial No. 201,739.

This invention relates to card games, and more particularly to card games of golf.

One of the objects of the present invention is to provide a card game of simple design, 5 adapted to be played in accordance with easily learned rules, while affording a suitable amount of variation in the scoring.

Another object is to increase by simple means, the number of possible combinations 10 for scoring with a limited number of cards.

Another object is to improve the distribution of cards in different classes representing different values of cards in a card game of golf.

15 In accordance with one aspect of the present invention a pack of cards contains a plurality of classes, each class containing cards of like value but differing in value from those in the other classes. One or more special cards in a special class depend for their 20 value upon companion cards selected from any of the classes.

The cards are particularly adapted for playing golf, the indicia on each card relating 25 to the number of strokes required to play one hole. The number of cards in any one class, each representing the same number of strokes, corresponds with the average number of plays, of the kind indicated, on the 30 cards in the class, occurring in an ordinary golf game in which the same number of holes are being played. A class of par cards, used as a reference class, contains the largest number of cards of any of the 35 classes. The number of cards in the other classes is successively less according to the degree of remoteness from the par class.

In the accompanying drawings, Figs. 1 to 6, inclusive, are face views of the different 40 kinds of cards making up a pack adapted for playing golf.

The indicia consisting of the digits 10 and the names 11 on the cards, relates to the number of strokes required to play a given hole. 45 A complete pack or deck, preferably consists of thirty-six cards, including two eagle cards, each valued at two strokes; eight birdie cards, each valued at three strokes; sixteen par cards, each valued at four strokes; six slice cards, each valued at five strokes; two hook cards, each valued at six strokes; and two stymie cards whose value ordinarily depends upon that of other cards selected from the pack, as explained hereinafter.

50 The pack thus consists of a plurality of classes of cards, any one class including

cards of the same kind, differing in value from those in the other classes. The number of cards in any given class corresponds approximately with the average number of 60 plays, of the kind indicated on the cards in the class, occurring in an ordinary golf game in which the same number of holes are being played. Considering the classes of cards arranged in a series, as shown in the drawing, 65 in the order of sequence of the numbers indicated by the cards, it will be seen that the par class contains the largest number of cards and that the number of cards in the other classes is successively less according to the 70 degree with which they are removed from the par class.

Game 1. Two players. An eighteen hole game of golf may be played by two players 75 as follows: The dealer thoroughly shuffles the cards and deals the first card, face up, to his opponent, dealing the second card to himself, the third to his opponent and so on, first to his opponent and then to himself until the thirty-six cards are dealt.

Each player lays his cards down with their faces up, opposite those of his opponent, in the order in which they are dealt. For instance, the seventh card dealt to the dealer is placed opposite the seventh card dealt 80 to his opponent. Each numbered card indicates by its number, the number of strokes required to play one hole. A stymie card counts one stroke more than the opponent's card placed opposite it, that is, when a stymie card comes opposite an eagle card, the stymie counts three, one more than the number on the eagle card. When two stymie 85 cards are placed opposite each other they both count seven strokes and the hole is tied. A player's score is obtained by adding together the strokes required to play the total 90 number of holes. The game is adapted for either medal or match play.

A nine hole game may be played by dealing only eighteen cards from the pack, the method of scoring being the same as described above.

For an eighteen hole game the highest 105 possible score is 84, the lowest possible score is 60, and the par or average is 74.

For a nine hole game the highest possible score is 48, the lowest possible score is 25, and the par or average is 37.

Game 2. Four players. A nine hole game may be played by four players as follows: The cards are shuffled and one card

is then dealt to each of the four player, beginning with the player at the left of the dealer. The lowest card wins the first hole. Successive holes are similarly played. In case of a tie, the player having the lowest total number of strokes up to that point in the game, wins the hole. When this total is tied, the hole is tied. In this game the stymie cards count seven. The score of any player is obtained by totaling the strokes he has made.

Game 3. One player. After shuffling the cards, they are taken one at a time from the top of the pack, the first card representing the first hole; the second card, the second hole; and so on up to the eighth hole. The cards remaining in the pack are then reshuffled and the ninth hole is played by drawing one more card from the pack. The score is obtained by adding the strokes of the nine cards.

It is to be understood that the present invention is not limited to the precise methods herein described for the purposes of illustration, and that many variations are possible in the representations on the cards and in the methods of playing, without departing from the invention.

I claim:

1. In a card game of golf, a pack of cards, each of which bears indicia relating to the number of strokes required to play one hole, said pack containing a plurality of classes of cards, said indicia being different in each

separate class but the same within the class, and a stymie class containing a card representing an initially undetermined number of strokes, said last mentioned number being dependent upon the indicia of a companion card selected from any of said classes.

2. In a card game of golf, a pack of cards containing a series of classes, each card in any one class bearing like indicia representing the number of strokes required to play one hole, said classes being arranged in said series in sequence according to the numbers represented by said indicia, said series containing a reference class having the largest number of cards, the number of cards in said other classes being successively less according to the degree of remoteness from said reference class.

3. In a card game of golf, a plurality of cards each bearing indicia of the number of strokes required to play a hole, said cards being divisible into different classes, the indicia of cards in any one class representing the same number of strokes, and the indicia of cards in different classes representing different numbers of strokes, the number of cards in any one class corresponding with the average number of plays, of the kind indicated in said class, occurring in an ordinary golf game in which the same number of holes are being played.

In witness whereof, I hereunto subscribe my name this 23rd day of June, 1927.

CHARLES H. DOLAN.
